UNITED STATES PATENT OFFICE

OSCAR H. SCHLEBECKER, OF FORT WAYNE, INDIANA, ASSIGNOR OF ONE-HALF TO
GEORGE W. SETTLES, OF FORT WAYNE, INDIANA

CANT HOOK FOR BARRELS

Application filed March 3, 1932. Serial No. 596,588.

This invention relates to improvements in cant hooks for barrels and particularly oil barrels of the steel drum type, and the object thereof is to provide a convenient tool for 5 turning barrels from rolling position so as to be stood on end, and which requires but little physical exertion to operate.

An illustrative embodiment of the invention is shown in the accompanying drawing, 10 in which:—

Fig. 1 is an end elevation of a barrel with an appliance embodying the invention applied thereto;

Fig. 2 is a side view of the appliance; and 15 Fig. 3 is a fragmentary side elevation of a barrel with the appliance in operative position thereon.

The illustrative embodiment of the invention consists of a lever 1, preferably formed 20 of a pipe, to one end of which is secured a plug constituting a cushion 2. Upon the lever adjacent its cushioned end is secured a fulcrum frame 3 by means of a pivot 4, the frame having side members 5, a foot 6 and a cross-brace 7. A grapple frame is secured to the lever 1 by means of a pivot 9 at a point thereon spaced back from the fulcrum frame. The 25 said grapple frame consists of a pair of divergent arms 8 connected by a cross-brace 10, and the lower end of each arm has a hook 11 formed thereon.

In use, the device is applied to the barrel 12 by placing the foot 6 of the fulcrum frame on the inner face of the end flange 13 of the barrel and then engaging the hooks 11 of the grapple-frame under the external end rim 14 thereof, after which by raising the outer end 30 of the lever its cushioned end is brought into contact with the barrel head 15. In this manner the barrel is firmly held in the grasp of the device while the lever is being manipulated to set the barrel on end or maneuver it about.

The lower ends of the arms 8 of the grapple frame are spaced widely apart and the foot 6 of the fulcrum frame is made wide so that the lever 10 when in operating position is braced substantially against lateral swinging movement relative to the barrel so that the 45 barrel may be moved while lying upon its

side by applying lateral force to the lever, or, the end of the barrel to which the appliance is applied may be raised by lifting upwardly upon the lever.

An advantage of the device is that it may be 55 readily applied to the barrel by simply placing the foot and the hooks 11 in their proper positions and then raising the lever so that its inner end bears against the barrel head, and it is also as readily removed from the 60 barrel by swinging the lever backwardly so that the grapple frame is moved out of engagement with the rim.

I claim:

1. A cant hook for barrels consisting of a 65 lever having on one end thereof a cushion, a fulcrum frame having divergent side members and a foot contiguous with the outer ends thereof, the opposite ends of said members being pivotally connected with said lever at a point thereon adjacent its cushioned end, and a grapple frame having divergent arms 70 and a crosspiece connecting same, the outer end of each arm having a hook formed thereon, the opposite ends of said arms having pivotal connection with said lever at a point 75 thereon spaced back from said fulcrum frame.

2. A cant hook for barrels consisting of a lever, a fulcrum frame having a laterally disposed foot at one end and pivotal connection 80 at its other end with said lever at a point adjacent one end thereof, and a grapple frame pivotally connected at one end with said lever at a point thereon spaced back from said fulcrum frame and being provided at 85 its outer end with hooks spaced widely apart.

3. A cant hook for barrels consisting of a lever, and two frames pivotally connected with said lever adjacent one end thereof at 90 points thereon spaced apart, one of said frames having a laterally disposed foot and the other frame being provided at its outer end with hooks spaced widely apart, said lever and frames being so disposed that when applied to a barrel said foot bears against the 95 inner face of the flange of the barrel and said hooks engage the external rim thereof, while the corresponding end of said lever has contact with the head of said barrel.

4. In a device of the class described, a lever 100

having pivoted frame members spaced apart adjacent one end thereof adapted when the device is applied to a barrel to have gripping engagement with the flange and rim members 5 of said barrel on the corresponding end thereof when the lever is raised and its inner end bears against the adjacent head of said barrel.

10 In testimony whereof I affix my signature.
OSCAR H. SCHLEBECKER.
